NATHAN JOHNSTON Inventor

UNITED STATES PATENT OFFICE.

NATHAN JOHNSTON, OF OAK CLIFF, TEXAS.

DESIGN FOR A REIN-GUIDE.

SPECIFICATION forming part of Design No. 29,627, dated November 8, 1898.

Application filed October 11, 1898. Serial No. 693,264. Term of patent 14 years.

To all whom it may concern:

Be it known that I, NATHAN JOHNSTON, a citizen of the United States, residing at Oak Cliff, in the county of Dallas and State of Texas, have invented and produced a new and original Design for a Rein-Guide, of which the following is a specification.

This invention relates to a new and original design for a rein-guide; and it has for its object to provide a design of this character which shall be both useful and ornamental.

The leading feature of the design resides in a rein-guide having a segmental guide-bar provided at one side with an offstanding approximately V-shaped bracing-loop and in a plane at substantially right angles to the disposition of said loop with a pair of spaced pendent supporting-legs projected downwardly from its under side.

A minor feature of the design is the guide-bar having its supporting-legs lying in substantially the plane of the terminals of the loop, which are joined to the bar, and in the supporting-legs having at their lower ends perforated terminal feet.

In the accompanying drawings, Figure 1 is a perspective view of a rein-guide embodying the herein-described design. Fig. 2 is a

plan view of the guide. Fig. 3 is a side view of the guide.

Referring to the accompanying drawings; the numeral 1 designates a guide-bar, which is of the segmental form shown in the drawings, and said guide-bar is provided, at one side thereof, with an offstanding approximately V-shaped bracing-loop 2. This bracing-loop 2 is provided with a rounded apex 3, and its inclined side members join at one end to the guide-bar, at points equidistant from the center thereof, and in the plane of the terminals of the bracing-loop are connected with the guide-bar. The latter is further provided with a pair of spaced pendent supporting-legs 4, projected downwardly from its under side and provided at their lower ends with perforated terminal feet 5.

What is claimed is—

The design for a rein-guide herein shown and described.

In testimony that I claim the foregoing as my own I have hereto affixed my signature in the presence of two witnesses.

NATHAN JOHNSTON.
